WRINGER

Charles W. Williams, Cleveland, Ohio

Application September 23, 1935, Serial No. 41,706

23 Claims. (Cl. 68—32)

This invention relates to a laundry wringer, which utilizes rotating pressure rolls to squeeze water from the clothes. It is a general object of this invention to provide a power-driven wringer which will prevent injury to the operator and which will enable the operator to straighten the clothes and the buttons thereon, while the material is being fed to the wringer, without fear of injury.

10 Heretofore, laundry wringers have been provided with a pair of horizontally disposed pressure rolls and an auxiliary roll beneath the pressure rolls and adapted to simultaneously coat with both pressure rolls, without shifting the auxiliary roll in the plane of the axes of the pressure rolls. These wringers, to a great extent, have been undesirable, due to their inability to feed varied types of material, such as are found in an ordinary household washing, to the 20 pressure rolls.

It is an object of this invention to provide a clothes wringer having a pair of pressure rolls; together with an auxiliary roll arranged to coat with either pressure roll and at the same time be positively rotated independent of the frictional contact between the auxiliary roll and its coacting pressure roll or the clothes therebetween. It is also an object of this invention to provide means to effect a reversal of the direction of rotation of such auxiliary roll when feeding from opposite sides of the wringer.

25 A further object of this invention is to provide a clothes wringer wherein the pressure rolls are power-operated, and wherein their rotation is automatically stopped when clothes of a predetermined thickness are fed to the wringer, or when the operator's hands are engaged by the auxiliary roll and its coacting pressure roll. This stopping is desirable in preference to an 30 automatic separation of the rolls, as it has been found that operators may become frightened by the shock of the pressure rolls automatically flying apart.

An additional object of this invention is to 35 provide opposite sides of the wringer with feed tables to coat with the auxiliary roll and its coacting pressure roll, and provide a substantially horizontal intake bite for the clothes.

Still another object of this invention is the 40 provision of a single shiftable mechanism to effect a reversal of direction of rotation of the auxiliary roll and a bodily shifting of the same when it is deemed necessary, and further, this mechanism may accomplish a shifting of the 45

drain board to drain liquid from one side of the wringer to the other.

Further objects of the invention will become more apparent from the following description, reference being had to the accompanying drawings, which illustrate preferred forms thereof. The essential characteristics of the invention will be set forth in the claims.

Referring now to the drawings, Fig. 1 is a perspective view of my improved wringer, together with the head to which it is fastened; Fig. 2 is a section taken in a horizontal plane through the pressure rolls, as indicated by the lines 2—2 on Fig. 6; Fig. 3 is a transverse section through the wringer, taken in a vertical plane passing through the axis of the auxiliary roll, as indicated by the lines 3—3 on Fig. 6; Figs. 4, 5 and 6 are transverse sections through the wringer, as indicated by lines 4—4, 5—5, 6—6, respectively, on Fig. 2; Fig. 7 is an end view of 20 the wringer, certain parts being broken away to show the drain board and auxiliary roll shifting mechanism; Fig. 8 is a section similar to Fig. 5, showing a modified form of feed table; Figs. 9 and 10 are similar to Figs. 5 and 6, respectively, showing a modified form of construction in which the auxiliary roll is shiftable horizontally; Fig. 11 is a sectional view taken along the irregular line 11—11 on Fig. 9.

As shown in Fig. 1, my improved wringer comprises a main frame 20, supported by a wringer head 21, which, in turn, supports a power shaft 22. The head is adapted to be positioned on the usual bracket or column formation, which forms a part of the present day washing machines and which carries a vertically extending power shaft adapted to be coupled with the shaft 22 of the wringer head 21 in the usual manner. The usual pair of bevelled gears within the head transmits the rotation of the shaft 22 at right angles to a shaft 23 (Fig. 3) which extends into the wringer frame 20. A supplemental frame 24 is provided, which is hingedly carried by the lower frame at 25, and which acts as a cover for the main frame of the wringer.

45 A pair of wringer rolls are disposed in a substantially horizontal plane within the wringer, and as shown in Fig. 5 comprise rolls A and B. Roll B is carried by a shaft 26, which is journalled at its ends in brackets 28, fastened by suitable bolts to bosses 30 of the supplemental frame. To compensate for wear and inaccuracy in manufacture, a shim is interposed between the bracket 28 and the bosses 30, and is extended as at 31 to overlie the journal blocks of the 50 55

pressure roll A, for a purpose to be hereinafter described.

The pressure roll A is pivotally mounted in the frame 20. As shown, this roll is mounted on a shaft 27 which is journalled at each end in bearing blocks 32. The blocks are each provided with a bolt 33 which is slidably mounted in a yoke 34. The yokes 34 are pivotally supported by respective pivot shafts 35 carried by the frame 20, the arrangement being such that the axis of the shafts 35 align with each other. Wringing pressure is applied to the roll A by suitable springs 36 which encircle the bolts 33 and react between respective yokes 34 and bearing blocks 32. The bolts are, as shown in Fig. 2 provided with suitable heads 37 which engage their respective yokes to prevent excessive movement of the roll in a direction away from the yokes, when the roll is not in operative wringing position.

The rolls A and B are forced into wringing relation with each other, against the pressure springs 36, when the supplemental frame 24 is swung about its pivots 25, the shims 31 engaging the top of the journal blocks 32, which carry the pressure roll A; forcing such blocks downwardly against the top of brackets 40 mounted in the lower part of the frame 20, and secured thereto by suitable bolts, and arranged to maintain the axis of the roll A a slight distance above a plane passing through the axis of the roll B and the axis of the pivot shafts 35.

The supplemental frame 25 is locked with respect to the frame 20 in a manner similar to that described in the copending application of Charles B. Williams, Serial No. 690,374. As there described, this locking means is manually operable by the action of the knobs N, one of which is carried by each end portion of the cover 24. These knobs are provided with pins 41 which extend through the cover 24 and consequent upon the depression of a knob swing a latch 42, against the action of a spring 43, and out of engagement with a pin 44 carried by the frame 20. When the cover 24 is swung against the lower frame, a cam surface 39 of the latch engages the pin 44 and together with the spring 43 causes the latch to automatically reengage the pin 44. A downward movement of the knob N releases the locking means, and due to the compression springs 36 and the fact that the axis of the roll A is retained above the plane of the axes of the pivots 35 and roll B, the roll A is forced upwardly. The roll A thus opens the wringer, by pushing against the unlatched cover 24, and rocking the same about its pivots 25.

A pair of strippers S and a deflector D coat with the pressure rolls A and B to strip clothes therefrom, as described and claimed in the above-mentioned copending application of Charles B. Williams, No. 690,374.

An auxiliary roll C, somewhat greater in diameter than the pressure rolls A and B, is disposed beneath them to feed clothes into the bite of such pressure rolls. In the preferred form of construction, shown in Figs. 2 to 7, inclusive, this roll comprises a rubber roll formed on a shaft 45, which is journalled at its ends in respective journal blocks 46 which are mounted for vertical movement in a slideway 47 formed in the brackets 40. Any means such as suitable slots extending vertically of the slideway and adapted to be engaged by projections on corresponding sides of the journal blocks may be used to maintain the same in coacting relation.

Coil springs 48 are interposed between the lower face of each journal block 46 and the respective brackets 40. These springs act to urge the auxiliary roll C upwardly into coacting relation with the pressure rolls A and B. The top of a slideway 47 in the bracket 40 is bridged by the bracket terminating the slideway at such a point that the roll C, when in its uppermost position, is maintained out of contact with both rolls A and B. However, the arrangement is such that the auxiliary roll is so positioned as to come as close to the pressure rolls as the irregularities in manufacture of the rolls will permit, without actually contacting with the pressure rolls. It has been found by experience that for the best operation, the roll C should at no time actually contact with the surface of rolls A and B.

A guide is provided to strip the clothes from the roll C and direct them upwardly into the bite of the pressure rolls A and B. As shown in Figs. 1 to 7, this guide comprises a member 50 which is freely movable in vertical slots 51 in respective brackets 40, thereby permitting the guide to lie against the roll C and rise and fall therewith.

Feed tables are provided to facilitate the feeding of the clothes into the bite between the auxiliary roll C and its coacting pressure roll A or B, as the case may be. As shown in Fig. 5, these feed tables may comprise a pair of arcuate members 52, one disposed on each side of the auxiliary roll C. The feed tables are provided with pintles 53 which are pivotally mounted in the brackets 40. Springs 62 interposed between the feed tables 52 and the brackets 40 hold the free edge of the respective feed tables 52 against the surface of the roll C. It should be noted that the edges of the feed tables 52, which contact with the roll C, terminate at such a point that they never reach the bites created between the roll C and its coacting pressure rolls. These feed tables facilitate the operation of the wringer, as they enable the operator to feed the clothes to the wringer in a substantially horizontal direction.

The auxiliary roll controls the driving connection between the wringer rolls and the power shaft 23 of the wringer head. As shown in Figs. 2 and 5, I illustrate a rock shaft 55 as extending substantially across the wringer and journalled in the brackets 40 (Fig. 6). Suitable arms 56 are secured to this rock shaft and are adapted to be engaged by respective ends of the auxiliary roll shaft 45 when the latter is depressed. The arrangement is such that, when the auxiliary roll is moved downwardly by a normal thickness of material, there will be no contact between the roll shaft and the arms 56. If, however, either the fingers of the operator or an excessive thickness of clothing pass into the bite of the auxiliary roll and a coacting pressure roll, the auxiliary roll will move downwardly, against the action of its springs 48, until its shaft 45 contacts with and rocks one or both of the arms 56 downwardly, thereby rocking the shaft 55, together with an arm 57 secured thereto, in a counter-clockwise direction (Fig. 4).

The rocking of the arm 57, as above described, acts to separate the driving connection between the pressure rolls and the source of power, namely, the drive shaft 23. As illustrated in Fig. 4, this driving connection comprises a gear 60 secured to the power shaft 23 and an idler gear 61 which meshes therewith. The idler gear 75

normally engages a gear 62 drivingly carried by the shaft 26 of the pressure roll B.

The power separation is accomplished by moving the idler gear 61 out of mesh with the roll gear 62. As shown, the idler gear is journalled on a shaft 63, which is carried by a lever 64, pivotally carried by the shaft 23. The arrangement is such that the gears 60 and 61 are constantly in mesh with each other.

10 The lever 64 is arranged to be swung about its pivot consequent upon the rocking of the arm 57, heretofore described, by a suitable spring 58 interposed between the lever 64 and the frame 20. The lever 64 is held in the position illustrated in 15 Fig. 4 by a latch 65 which is pivoted to the frame 20 as at 66 and normally engages a pin 67 in the lever 64. The latch is rocked out of engagement with the pin by a link 68 which is pivotally connected between the latch 65 and the arm 57. A 20 suitable spring 69 normally acts to maintain the latch engaged and the lever 57 in its uppermost position.

When either an excess thickness of clothing or the operator's hand enters the bite of the auxiliary roll C and its coacting pressure roll A or B, the roll C is forced downwardly against the action of the compression springs 48, until it rocks one or both of the rock-arms 56, together with the shaft 55, and causes the arm 57 to draw 30 the link 68 downwardly, rocking the latch 65 clockwise about its pivot, causing it to disengage the pin 67. The spring 58 then rocks the arm 64 counter-clockwise, causing a separation of the gear 61 from the gear 62, thereby stopping the 35 rotation of the pressure rolls. A second latch formation 75 in the latch 65 coacts with the pin 67 and limits the movement of the lever 64 and the latch 65.

In the normal operation of the wringer, the 40 operator depresses the knob N immediately after the automatic disconnection of the power mechanism takes place, and releases the cover latching mechanism, causing the supplemental frame 24 to rock upwardly about its pivots 25, thereby 45 permitting the operator to extract the excess thickness of clothes from between the wringer rolls. The subsequent lowering of the cover 21 causes the pin 70, carried thereby, to act against a cam surface 73 formed at the upper 50 end of the lever 64 and return such lever to its original position, permitting the latch formation 76 of the latch 65 to reengage the pin 67, thus 55 restoring the driving connection to the pressure roll B. When the excess thickness of clothes has been removed from the wringer, the pressure of the auxiliary roll C against the arms 56 is removed, whereupon the spring 69 causes the latch 65 to return to its normal position and engage the pin 67 of the lever 65.

60 The auxiliary roll C is rotated independent of frictional engagement with its coacting pressure roll or the material therebetween. As shown in Fig. 6, a gear 80 is fastened to each of the pressure roll shafts 26 and 27, at the ends thereof, farthest from the power head. Disposed in the 65 same vertical plane with these gears is a gear 81, carried by the shaft 45 of the auxiliary roll C. The respective diameters of the gears 80 and 81 are proportional to the diameters of the associated rolls A, B and C. A suitable idler gear 83 is selectively interposed between either of the gears 80 and the gear 81. Thus, when the roll C is driven by such gearing, its surface speed is the same as that of its coacting pressure roll.

75 The idler gear 83 is carried by a shaft 84, jour-

nalled in an arm 85, which is pivotally mounted on the shaft 45 of the auxiliary roller C. When clothes are fed into the left-hand side of the wringer, as shown in Fig. 5, the relation between these various gears will be as shown in Fig. 6, 5 the auxiliary roll C being positively driven to provide a bite with the pressure roll A. However, when the clothes are fed from the right hand side of the wringer, the idler gear will be positioned to coact with the left-hand gear 88, 10 thereby reversing the direction of rotation of the auxiliary roll C to provide a bite with the roll B.

The gearing is so arranged that when an excess thickness of material passes between either the rolls A or B, and the roll C, the latter roll will 15 drop to such an extent that the gear 83 will cease to engage its coacting gear 80. When such excess thickness is removed, the gears will automatically reengage due to the action of the auxiliary roll springs 54.

Mechanism is provided to effect a shifting of the idler gear 83 to engage either gear 80 desired. Such mechanism is shown in Figs. 7 and 11, and comprises a manually operable lever 90 mounted outside of the wringer on a pin 91 which is journaled in and extends through the frame 20. On the interior of the wringer the pin 91 has secured thereto an arm 92, provided with a slot 93, adapted to receive the shaft 84 which carries the idler gear 83.

30 It will be apparent from Fig. 7 that when the lever 90 is moved from one side of the wringer to the other, the idler gear 83 moves from engagement with one gear 80 to engagement with the other gear 80. The sizes of these gears is 35 such, that the idler gear 83 is entirely out of contact with one gear 80 before it engages the other gear.

In addition to reversing the direction of rotation of the auxiliary roll C, the arm 90 is utilized 40 to effect a shifting of the drain board, and its associated wringer closure members. The drain board shown in Figs. 5 and 7, together with closure members which selectively close the side feed openings of the wringer, are substantially 45 the same as those shown, described and claimed in the copending application of Charles B. Williams, Serial No. 690,374.

Briefly, such drain board comprises a trough-shaped member 95, pivotally disposed beneath an opening 95a in the bottom of the frame 20. This drainboard is secured to a shaft 96 journalled in a bracket 96a carried by the frame 20 to enable it to be tilted to divert the water wrung from the clothes to either side of the wringer, as desired by the operator. The closure members each comprise a plate 97 substantially the size of the respective side openings 98 in the wringer frame. These closure members are pivoted as at 99 to the walls of the frame member 20 adjacent their respective openings 98. The closure members are arranged so that when one, as, for instance, the left-hand member in Fig. 5, is tilted downwardly to permit access to the wringer from that side, the other closure member, for instance, the right-hand member, will be swung upwardly to a closed position to prevent access to the other side of the wringer. The position of the closure member is dependent upon the position of the drainboard. As shown, a link 100 is pivotally connected between each closure member and its respective side of the drainboard.

The drainboard is tilted by the operating lever 90, heretofore described. Hence, when the wringer is set to permit feeding of material from the 75

left-hand side, as in Fig. 5, the drain board will be tilted to divert the water toward that side and the auxiliary roll will be rotated in a clockwise direction. The reverse will be true if the wringer is set to feed from the opposite or right-hand side. As shown in Fig. 7, the lower end of the lever 90 is provided with a fork 101 arranged to engage a pin 102 in a lever 103 pivoted at 104 to the frame 20. This lever in turn carries a pin 105, which engages a forked lever 106 which is secured to the drainboard rockshaft 96.

Thus, when the handle 90 is drawn from one side of the wringer to the other, it not only effects a shifting of the idler gear 83 to reverse the direction of rotation of the auxiliary roller C, but also effects a shifting of the drainboard 95, and the closure members 97.

In Fig. 8 I illustrate a modified form of feed table. As there shown, the feed table comprises an arcuate shield 106 embracing the auxiliary roll C. The top surface of this feed table is provided with a slot through which the upper region of the auxiliary roll C protrudes to permit coaction of such roll with either pressure roll A or B. This feed table or shield 106 terminates, at each end of the roll C, in end members 107 adapted to engage and be carried by the journal blocks 46 which support the auxiliary roll shaft 45. In this construction, the arcuate feed table and the guide 50 both move up and down as a unit with the auxiliary roll C. It will be noted that this modification also permits the use of a substantially horizontal intake.

The wringer may be constructed with the auxiliary roll C shiftable from side to side, to coact with either pressure roll as desired. Such a modification is shown in Figs. 9, 10 and 11. Here the entire wringer is substantially the same, except for the mechanism directly concerned with the auxiliary roll.

As shown in Figs. 9 and 11, the auxiliary roll C is carried in journal blocks 110, which are urged upwardly toward the pressure rolls by compression springs 111. A stripper guide 112 is provided similar to the stripper guide 50 and is vertically reciprocable in slots carried by the frame brackets 113. This guide is retained in coaction with the auxiliary roll C by a link 114, which is pivotally carried by the roll shaft 45.

To permit lateral movement of the auxiliary roll C, enlarged openings or guideways 115 are provided in frame brackets 113.

In order that the auxiliary roll C will contact with its coacting pressure roll, the surfaces of the bracket 113 which contact with the journal blocks 110 are disposed slightly above the highest position reached by the journal 110, which selectively occupies recesses 116 formed in such surfaces.

The auxiliary roll C is shifted from side to side by a manually operable lever 120 mounted on a shaft 121 outside of the wringer. This shaft extends through the frame 20 and on its inner end is provided with a downwardly extending arm 122. This arm is provided with a slot 123 adapted to receive the shaft 45 of the auxiliary roll C. The lower end of the arm 122 is slotted, and coacts with the pin 105 of the arm 106 which tilts the drainboard.

In the modified form shown in Figs. 9-11, where the roll C is shiftable, the shaft 96 is extended across the wringer and is operatively connected to a member 122 on each end of the roll. Thus, the member 122 directly connected to the handle 120 is aided by a similar member pivoted

to the frame bracket 40 on the other side of the roll C and operated through the shaft 96 to effectively shift that roll into coaction with either pressure roll desired. As in the preferred form, the auxiliary roll C is permitted sufficient downward movement until in a predetermined position it engages the rock arms 56 to disconnect the wringer rolls from the source of power, as heretofore described. Stops 125 are provided to limit the downward movement of the feed table members 52, when the auxiliary roll is moved out of contact therewith, although a feed table, as shown in Fig. 8, at 106, may be provided, in which case the stops are not necessary.

To drive the auxiliary roll of the modified form, a gear 130 having a pitch diameter substantially equal to the diameter of the auxiliary roll is secured to its shaft 45 and is arranged to selectively mesh with either of a pair of inter-engaging gears 131 carried by respective pressure roll shafts 26 and 27. Thus, when the auxiliary roll C is shifted from one side of the wringer to the other, the gear 130 is moved from engagement with one gear 131 into engagement with the other gear 131. A hump on the underside of the bracket guideway 115 dividing the recesses 116 is provided to cause the journals 110 to be cammed downwardly, whereby the gear 130 is completely disengaged from one gear 131 before engaging the other.

It will be seen from the foregoing description that I have provided an efficient wringer especially adapted for use in connection with a power operated domestic washing machine and that such wringer affords a high degree of safety to the person of the operator, and greatly facilitates the feeding of clothes or other materials to be wrung into and through the wringer.

I claim:

1. In a wringer, a pair of horizontally disposed pressure rolls, an auxiliary roll disposed beneath and shiftable to coact with either of the pressure rolls as desired and means to selectively rotate said auxiliary roll independently of clothes fed to the wringer in a direction to provide a bite with the pressure roll with which said auxiliary roll is moved to coact.

2. In a wringer, a pair of pressure rolls, an auxiliary roll adapted to coact with one of the pressure rolls to provide a bite therewith and a feed table to guide clothes into said wringer, comprising a member having one edge substantially in contact with said auxiliary roll and means to support said member for bodily shifting relative to a pressure roll.

3. In a wringer, a frame, a pair of pressure rolls mounted in said frame, an auxiliary roll adapted to coact with one of the pressure rolls to provide a bite therewith and a feed table to guide clothes into said bite, comprising a member pivotally carried by said frame and having one edge substantially in contact with said auxiliary roll, and resilient means to maintain said edge in contact with the auxiliary roll.

4. In a wringer, a frame, a pair of pressure rolls mounted in said frame with an upwardly extending bite, and power operated guide means beneath said pressure rolls and reversible in direction of surface movement without bodily shifting to receive material from either side of the wringer and guide it into the bite of the pressure rolls.

5. In a wringer, a frame, a pair of pressure rolls mounted in said frame with an upwardly extending bite, power operated guide means

reversible in direction of surface movement without bodily shifting to receive clothes from either side of the wringer to guide clothes to the bite of the pressure rolls and means acting in conjunction with said first named guide means, to facilitate the guiding of clothes into the bite of said pressure rolls.

6. In a wringer, a frame, a pair of pressure rolls mounted in said frame with an upwardly extending bite, power operated guide means reversible in direction of surface movement without bodily shifting to receive clothes from either side of the wringer, means to operate said guide means independently of clothes fed to the wringer to guide clothes to the bite of the pressure rolls and means to direct clothes from said first guide means into the bite of the pressure rolls.

7. In a wringer, a pair of pressure rolls arranged in a substantially horizontal plane, an auxiliary roll, shiftable means to support said roll for coaction with either pressure roll to provide a bite therewith and a feed table carried by said roll supporting means to guide clothes into said bite and comprising a member having one edge substantially in contact with said auxiliary roll and movable therewith.

8. In a wringer, a pair of pressure rolls, an auxiliary roll adapted to coact with both pressure rolls simultaneously and a guide positioned with respect to said auxiliary roll to guide clothes from the bite of the auxiliary roll and either coacting pressure roll into the bite of the pressure rolls.

9. In a wringer, a pair of pressure rolls, an auxiliary roll adapted to be moved to coact with either pressure roll to provide a bite therewith, means to rotate the auxiliary roll independently of clothes fed to the wringer and a guide disposed between the rolls to strip clothes from the auxiliary roll.

10. In a wringer, a pair of coacting pressure rolls disposed in substantially the same horizontal plane, an auxiliary roll mounted with its axis in a vertical plane, substantially normal to the first-named plane and passing substantially through the bite of the pressure rolls, said auxiliary roll being substantially in contact with both pressure rolls, and a guide arranged to rest on said auxiliary roll between the three rolls, and means to restrict the movement of said guide to movements in a substantially vertical plane.

11. In a wringer, a pair of pressure rolls, disposed in the same substantially horizontal plane, resilient means adapted to retain said pressure rolls in wringing relation, an auxiliary roll disposed beneath said pressure rolls and adapted to coact with either pressure roll desired without shifting said auxiliary roll, and a guide disposed between the three rolls adapted to strip material from the auxiliary roll and guide the same into the bite of the pressure roll.

12. In a wringer, a pair of pressure rolls disposed in a substantially horizontal plane, resilient means adapted to urge said pressure rolls into wringing relation, an auxiliary roll disposed beneath said pressure rolls and adapted to coact with either pressure roll without horizontal shifting, and means to positively rotate said auxiliary roll independent of clothes fed to the wringer to cause said auxiliary roll to rotate in the same direction as the pressure roll with which it is coacting to provide a bite for clothes fed to the wringer, and means to automatically

stop the rotation of the roll consequent upon the passing into the wringer of material thicker than a predetermined thickness.

13. In a wringer, a pair of horizontally disposed pressure rolls, an auxiliary roll disposed beneath and shiftable to coact with either of the pressure rolls as desired, a drainboard shiftable to divert liquid to either side of the wringer, means to selectively rotate said auxiliary roll independently of clothes fed to the wringer in a direction to provide an intake bite with the pressure roll with which said auxiliary is moved to coact, and means to reverse the direction of rotation of the auxiliary roll and simultaneously shift the drainboard to divert liquid from the side of the wringer providing said intake bite.

14. In a wringer, a frame, a pair of horizontally disposed pressure rolls mounted in a substantially horizontal plane in said frame, an auxiliary roll adapted to coact with either pressure roll to provide a bite therewith and a feed table to guide clothes into said bite, comprising a pair of members pivotally carried by said frame on either side of the auxiliary roll, each having one edge positioned to substantially contact with said auxiliary roll and resilient means to maintain said members in substantial contact with the auxiliary roll on opposite sides thereof.

15. In a wringer, a pair of pressure rolls arranged in a substantially horizontal plane, an auxiliary roll rotatably mounted in the frame, an arcuate feed table embracing the upper portion of the auxiliary roll and extending from one end to the other thereof, and having a slotted opening in its upper face through which the periphery of the auxiliary roll projects, and resilient means to maintain the auxiliary roll projecting through the opening in the table and urge such roll toward the two pressure rolls.

16. In a wringer, a frame, a pair of pressure rolls mounted in a substantially horizontal plane in said frame, an auxiliary roll adapted to coact with either pressure roll to provide bites therewith and a feed table on each side of said auxiliary roll to guide clothes into either of said bites, and a stripper guide adapted to guide clothes from the bite of the auxiliary roll and its coacting pressure roll into the bite of the pair of pressure rolls.

17. In a wringer, a pressure roll, a second pressure roll movable away from said first pressure roll, an auxiliary roll positioned to coact with both pressure rolls, power mechanism to drive said rolls, a separable driving connection from said mechanism to said rolls, means operable upon a predetermined separation between said auxiliary roll and one of said pressure rolls to disconnect said driving mechanism to stop the rotation of said rolls, means to move said rolls apart and means acting consequent upon moving said rolls together to restore said driving connection.

18. In a wringer, a pressure roll, a second pressure roll movable away from said first pressure roll, an auxiliary roll positioned to coact with both pressure rolls, power mechanism to drive said rolls, a separable driving connection between said rolls and said mechanism, resilient means to urge said pressure rolls together, means operable upon a predetermined separation between said auxiliary roll and one of said pressure rolls to disconnect said driving connection, means to remove the pressure of said resilient means, and means to simultaneously restore said

driving connection and restore the pressure of said resilient means on said rolls.

19. In a wringer, a frame, a pair of pressure rolls mounted in the frame, an auxiliary roll positioned to coact with either pressure roll, resilient means to urge said auxiliary roll toward said pressure rolls to provide bites between said auxiliary roll and each pressure roll, a feed table on each side of said auxiliary roll to guide clothes into the bite of said auxiliary roll and the adjacent pressure roll, a stripper guide disposed between the three rolls to guide clothes from either auxiliary roll bite into the bite of the two pressure rolls, means to rotate said auxiliary roll independent of clothes fed to the wringer, means to render inoperative said rotating means when clothes of a predetermined thickness are fed to the wringer, means to separate said pressure rolls and means to simultaneously move said pressure rolls together and render effective said operating means.

20. A three-roll wringer to which clothes may be fed from either side without bodily shifting the rolls, comprising a frame, three rolls carried by said frame in substantially triangular arrangement, with one roll coacting with each of the others to provide an intake bite and a pressure roll bite respectively, a guide member located between the three rolls and adapted to guide clothes from the intake bite to the pressure roll bite.

21. A three-roll wringer to which clothes may be fed from either side comprising a frame, three rolls carried in said frame in substantially triangular arrangement with one roll coacting with each of the other two to provide an intake bite and a pressure bite respectively, a guide

member located between the three rolls and adapted to guide clothes from the intake bite to the pressure roll bite, power means to rotate said wringer rolls and means acting consequent upon feeding a predetermined thickness of material to said intake bite to stop the rotation of said rolls.

22. A three-roll wringer to which clothes may be fed from either side thereof comprising a frame, three rolls carried by said frame in substantially triangular relation, one of said rolls coacting with each of the other two to provide an intake bite and a pressure roll bite respectively, resilient means to retain said rolls in the aforementioned triangular relationship, a gear carried on one of said roll shafts, a gear carried on another of said roll shafts and an idler gear interposed between said gears to rotate the second gear and its roll consequent upon rotation of the first gear and its roll.

23. A three-roll wringer to which clothes may be fed from either side without bodily shifting the rolls, comprising a frame, three rolls mounted in said frame in triangular relation, said rolls being positioned to provide an intake bite at each side of the wringer, one of said rolls coacting with a second roll to form the intake bite on the side of the wringer desired and also coacting with the third roll to provide a pressure roll bite, and a guide means located between the three rolls to receive clothes from the intake bite and guide them to the coacting pressure roll bite, and means acting consequent upon feeding a predetermined thickness of material to said intake bite to stop the movement of material through the wringer.

CHARLES W. WILLIAMS.
